UNITED STATES PATENT OFFICE

2,491,127

COMBINATION CURTAIN ROD AND SHADE
ROLLER BRACKET

Harold R. Morton, Carmichael, Pa.

Application August 31, 1945, Serial No. 613,722

1 Claim. (Cl. 248—253)

1

The present invention relates to new and useful improvements in fixtures for attaching curtain rods and shade rollers to a window frame and more particularly to a combination bracket for the curtain rod and shade roller by means of which the curtain rod and shade roller may be secured in adjusted position on the window frame without necessitating the use of nails, screws or similar fastening devices which might mar the appearance of the window frame.

An important object of the present invention is to provide a combined curtain rod and shade roller bracket of this character embodying adjustable means for the shade roller and by means of which rollers of various lengths may be secured in position on the bracket.

A still further object of the invention is to provide a bracket of this character for supporting a curtain rod, the curtain rod including telescoping section for adjusting the rod in accordance with variations in the width of the window frame and also providing spring means connecting the sections of the curtain rod to prevent spreading movement thereof.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a front elevational view.

Figure 2 is a top plan view.

Figure 3 is an end elevational view.

Figure 4 is a sectional view of one end of the curtain rod and shade roller taken on a line 4—4 of Figure 1.

Figure 5 is an enlarged perspective view of one of the shade brackets, and

Figure 6 is a fragmentary perspective view of one end of the curtain rod.

Referring now to the drawings in detail wherein for the purpose of illustration I have disclosed a preferred embodiment of the invention, the numeral 5 designates one of the attaching brackets generally which includes a front L-shaped plate 6 and a rear L-shaped plate 7.

The front plate 6 includes a rearwardly projecting flange 8 at the outer end thereof posi-

2

tioned against one side of the forwardly projecting flange 9 of the rear plate 7.

The flange 9 is formed with upper and lower horizontally extending slots 10 adapted for receiving bolts and wing nuts 11 carried by the flange 8 for securing the front plate 6 in forwardly and rearwardly adjusted position relative to the rear plate 7.

One of the brackets 5 is adapted for positioning 10 at each side of a window frame 12, with the rear plates 7 inserted behind the frame, the brackets 5 at the opposite sides of the window being connected by a coil spring 13 extending across the top of the window frame.

15 Each of the front plates 6 is formed with a horizontally extending slot 14 adapted for receiving a bolt and nut 15 inserted through a flange 17 of an angular shade roller bracket 18 for attaching the bracket in horizontally adjusted position in the slot 14, the flange having a forwardly projecting arm 19 of a type adapted for supporting one end of a shade roller 20 thereon. The arms 19 of the respective brackets may thus be adjusted to accommodate rollers of various lengths.

20 The front of the plate 6 at its lower edge is formed with a horizontal trough or channel 21 slidably receiving the lower edge of the flange 17 to prevent tilting of the bracket on the front plate 6.

25 The upper front surface of the plate 6 is formed with a pair of vertical sockets 22 in which are received the downturned ends of rods 23 secured in the flattened ends 24 of hollow telescoping curtain rods 25. The sections of the rods are secured to each other by coil springs 26 which also serve to draw the brackets against the opposite side edge of the window frame.

30 In view of the foregoing description taken in conjunction with the accompanying drawings it is believed that a clear understanding of the construction, operation and advantages of the device will be quite apparent to those skilled in the art. A more detailed description is accordingly deemed unnecessary.

35 It is to be understood, however, that even though there is herein shown and described a preferred embodiment of the invention the same is susceptible to certain changes fully comprehended by the spirit of the invention as herein described and the scope of the appended claim.

40 What I claim is:

45 A combined curtain rod and shade roller fixture comprising a pair of adjustable plates, one plate being adapted for engagement behind a

window frame and the other plate being adjustable outwardly in front of the frame, a shade roller bracket adjustable horizontally on said last named plate and including an angular flange, an edge trough on the last named plate slidably receiving one edge of the flange to prevent tilting of the flange on the plate, and spring means yieldably connecting a pair of the fixtures in clamping engagement at opposite edges of a window frame, sockets on the front surface of 10 said last named plate, adjustable curtain rods including telescoping sections having down-turned pins at their ends positioned in said sockets, and coil springs yieldably connecting the sections of the curtain rods and also exerting their influence on the fixtures to maintain the latter in clamping position on the frame. 15
